UNITED STATES PATENT OFFICE.

FRANK A. DECKER, OF PHILADELPHIA, PENNSYLVANIA, ASSIGNOR, BY
MESNE ASSIGNMENTS, TO DECKER ELECTRICAL MANUFACTURING
COMPANY, OF WILMINGTON, DELAWARE.

BATTERY.

No. 857,606.

Specification of Letters Patent.

Patented June 25, 1907.

Application filed March 30, 1904. Serial No. 200,847.

To all whom it may concern:

Be it known that I, FRANK A. DECKER, a citizen of the United States, residing at Philadelphia, in the county of Philadelphia and 5 State of Pennsylvania, have invented certain Improvements in Batteries, of which the following is a specification.

The leading object of my invention is to obtain a compact and light battery providing for the more ready renewal, distribution, and retention and more active operation of the elements than has heretofore obtained.

The nature and characteristic features of the improvements will more fully appear by 15 reference to the following description and the accompanying drawings in illustration thereof, of which:—

Figure 1 represents a top plan view of a battery embodying my invention: Fig. 2 represents a sectional side elevation of the construction shown in Fig. 1: Fig. 3 represents a sectional view taken on the line 3—3 of Fig. 2: Fig. 4 represents a sectional view taken on the line 4—4 of Fig. 2: Fig. 5 represents a top plan view of a modified form of the invention, part of the distributor or distributing lid being broken away to show the interior: and Fig. 6 represents a sectional side elevation of the modified construction 30 shown in Fig. 5.

Referring to the drawings, the jar 1 is provided with the ribs 2 which support the porous diaphragms 3, of usual material. The diaphragms are provided with the intersecting strengthening ribs 4 and the flanged borders 5 and 5^a, the borders being joined together to form cups or compartments 6 and 6^a. The borders 5^a of the alternate diaphragms are reduced to permit the insertion 40 of the ribs 7^a of the conductors 7 which make contact with the electrodes 8, connecting them in multiple relation. The electrodes 8 (suitably of zinc), in the form of fragments, as balls, granules, scrap or the like, are fed, as required, through the openings 10^a in the distributor or distributing lid 10 and are held in place by plates 9 (suitably of wood or metal electro-negative to the fragmental electrodes) having the slots 9^a therethrough 45 to permit free circulation of fluid and its access to the electrodes, the plates being sustained by the diaphragm ribs 4. The compartments 6 contain the plate electrodes 11

(suitably of carbon) having the ribs 11^a thereon which, with the diaphragm ribs 4, 55 space the plates between the diaphragms forming the walls of the compartments and provide for free circulation of the fluid. The plate electrodes have the projections or terminals 11^b which extend through the 60 apertures or terminal openings 10^b of the distributor and are connected in multiple by the conductor 12, the distributor having the closures 10^c provided with the gas vents 10^d for the compartments 6, as shown in Figs. 1 65 and 2, or for part of each compartment as shown in Fig. 5.

Referring to Figs. 2, 3 and 4, the tube 13 passes through the bottom of the jar, and the branch 13^a passes through the bottom of the 70 diaphragms, the branch having an orifice 13^b which discharges into the bottom of the side compartment 6, connected with the remaining compartments 6 by a tube 14 having the orifices 14^a, the tubes being of nonconducting materials and of such section as to afford the necessary resistance and being used for charging and discharging these compartments connected therewith. The tube 15 passes through the bottom of the jar to the 80 compartment 16 which communicates with the compartments 6^a through the orifices 6^b in the bottoms thereof, by which these compartments may be charged or drained.

Referring to Figs. 5 and 6, as in Figs. 3 and 85 4, a tube 13^a passes through the bottoms of the diaphragms and communicates with the end compartment 6, which communicates with the remaining compartments 6 by a tube 14, but in this case the tube 13^a is connected to a tube 13^b which rises to the height 90 of the compartments and descends to the bottom, its lower end lying in the flared tube mouth 17 opening through the bottom of the jar and around the end of the tube 13^b. The 95 bottom of the compartments 6^a are provided with the orifices 6^b, as shown in Figs. 4 and 6. In this case the compartments are charged by forcing a fluid through the tube mouth 17 into the compartment 16, whence it passes 100 through the orifices 6^b into the compartments 6^a, which are filled and overflow through the notches 18 into the compartments 6, washing down materials as salts or 105 depolarizers deposited in the tops of these compartments. In draining, the fluid dis-

charges from the compartments 6^a, through the orifices 6^b and the mouth 17, induces a discharge from the compartments 6 through the tubes 13^a and 13^b, the compartments 5 being emptied by the siphonic action thus set up.

The modified distributor or distributing lid shown in Fig. 5 has one-half provided with slotted openings 10^a communicating with the compartments 6 and the closures 10^c covering the compartments 6^a, while the other half has the slotted opening 10^a communicating with the compartments 6^a and the closures 10^c covering the compartments 6^b, the closures being provided with the vent 10^d. Each set of compartments is thereby adapted to be charged through the cover, with the material for renewing the electrodes or with a depolarizer in the form of a soluble salt.

Having described my invention, I claim:

1. In a battery, a compartment having imperforate walls of porous material, a fragmental electrode in said compartment, and 25 means in said compartment for permitting the free circulation of fluid and contact thereof with said electrode, substantially as specified.

2. In a battery, a compartment having 30 imperforate walls of porous material, a perforated plate dividing said compartment, and an active fragmental element retained in said compartment by said plate, substantially as specified.

3. In a battery, a compartment comprising 35 a pair of diaphragms, one of said diaphragms having ribs in said compartment, a perforated plate in said compartment supported by said ribs, and an active fragmental 40 element between said plate and the other of said diaphragms, substantially as specified.

4. In a battery, a plurality of compartments comprising flange bordered diaphragms joined together, a fragmental electrode 45 in one of said compartments, and a plate electrode having a projection thereon for engaging a conductor in the other of said compartments, substantially as specified.

5. In a battery, a plurality of compartments comprising flange bordered diaphragms joined together, a perforated member dividing one of said compartments, a fragmental electrode retained by said perforated member, and a ribbed plate electrode 55 in the other of said compartments, substantially as specified.

6. In a battery, a compartment comprising diaphragms having intersecting ribs and flanged borders, an active fragmental element 60 in said compartment, and means for retaining said fragmental element and providing for the circulation of fluid in said compartment, substantially as specified.

7. In a battery, a cell, a plurality of compartments therein, electrodes in said com-

partments, and a conductor in said cell making electrical contact with said electrodes through the vertical end walls of said compartments, substantially as specified.

8. In a battery, a plurality of compartments comprising flange bordered diaphragm joined together, each of said diaphragms having its parts composed of homogeneous material, and a conductor having contacts penetrating the borders of the alternate compartments, substantially as specified. 70

9. In a battery, a plurality of compartments comprising flange bordered diaphragms joined together, a conductor having contacts extending through the borders of the alternate compartments, electrodes in said compartments connected with said contacts, electrodes in the remainder of said compartments, and a conductor connecting said last named electrodes, substantially as specified. 80

10. In a battery, a distributor comprising elongated openings of greater length than width adapted for disseminating a fragmental electrode, in combination with compartments registering with said openings, said distributor having means for distributing such fragmental electrode in each of said compartments substantially as specified.

11. In a battery, a distributor having feeding and terminal openings, compartments fed 95 through said feeding openings, and electrodes having terminals in said terminal openings, substantially as specified.

12. In a battery, a plurality of compartments, and a distributing lid for said compartments, said lid having openings therethrough for feeding alternate compartments, and closures extending over intermediate compartments, substantially as specified. 100

13. In a battery, a plurality of compartments, and a distributing lid for said compartments, said lid having openings therethrough for feeding and closures extending over compartments registering therewith, substantially as specified. 105

14. In a battery, a plurality of compartments comprising flange bordered diaphragms joined together, a tube passing through the borders of said compartments and having orifices communicating with alternate compartments, and orifices through the bottoms of compartments separated from said tube orifices, substantially as specified. 110

15. In a battery, a plurality of compartments comprising flange bordered diaphragms joined together, and a tube extending through the lower borders of said diaphragms and communicating with one of said compartments, said tube rising approximately to the top of said compartments and descending to the bottom thereof, and an orifice for passing a fluid, said orifice containing the end of said tube, substantially as specified. 115

16. In a battery, a cell, a plurality of compartments therein, and electrodes in said compartments electrically connected within said cell in multiple relation through the side walls of said compartments, substantially as specified.

17. In a battery, a receptacle having an aperture in the bottom thereof, a plurality of compartments having openings in the bottoms thereof, said compartments being removably supported in said receptacle and above the bottom thereof, and means per-

mitting the circulation of fluid in said receptacle beneath said compartments, substantially as specified.

In testimony whereof I have hereunto set my hand this 28th day of March, A. D. one thousand nine hundred and four, in the presence of the subscribing witnesses.

FRANK A. DECKER.
